SIGNALING SYSTEM

Clarence E. Beach, Binghamton, N. Y.

Application February 19, 1940, Serial No. 319,628

25 Claims. (Cl. 177—369)

This invention relates to signaling systems, and more particularly to signaling systems of the type often designated as "auxiliary systems" and having auxiliary or sub-stations for causing signaling activity of associated main signal initiating stations.

This invention is especially suited, although by no means limited, to use in connection with circuits including code signal formulating main stations, in which circuits current flow is normally maintained, and between which circuits and the ground, or other common return conductor, an electromotive force is normally maintained whereby response to signal formulation may be effected notwithstanding various abnormal circuit conditionings.

Signaling systems have heretofore been devised in which each main station comprises a starting or tripping magnet for energization by current flow from the main fire alarm signaling circuit intended for response thereto, which magnet is normally short-circuited by a loop serially including sub-stations operable to interrupt current flow in the loop for the purpose of setting the main station into action. Such systems are frequently designated as "shunt type auxiliary systems," and main stations of such systems are frequently referred to as "auxiliarized fire alarm boxes." Disclosure of shunt type systems may be found in applicant's Patent No. 1,093,679, dated April 21, 1914.

Conventional forms of fire alarm systems utilizing code formulating stations, of types generally such as that disclosed by the patent just referred to, provide circuits often serially including a score or more of such boxes, and it has been found to be desirable to incorporate into such systems facilities whereby loss of code signals may be minimized or completely avoided, notwithstanding the development of circuit defects such as breaks and grounds, as well as crosses whereby one or more boxes are short circuited.

Applicant's Patent No. 1,999,859, dated April 30, 1935, not only discloses fire alarm box signaling mechanism which, when set in action, will formulate the intended code signal by alternately breaking and closing its associated circuit, subject to so-called, "non-interference and succession" control as well understood by those skilled in this art, but that patent further discloses means for effecting formulation of the code signal in a path between one, the other or both sides of the series circuit and the ground or other so-called "common return" or "independent" conductor, following determination by such mecha-

nism that circuit conditions are abnormal to an extent continuously impairing or preventing intended response to impulses formulated merely in the normally effective path.

It is evident that the addition of prior forms of so-called "auxiliarizing equipment" to mechanism having functional characteristics in accordance with said second named patent, leaves such equipment dependent upon effectiveness of current flow in the main signal circuit, and will therefore fail to set the master box in action during occasions when there is no current flow in the portion of the main signaling circuit in which such master box is connected, either because such box is short-circuited or because current flow is interrupted by an accidental break in the circuit at one side or the other of such box.

It is, therefore, one of the principal objects of this invention to provide an auxiliary signaling system in which operation of a sub-station will result in its associated master station being set into operation notwithstanding any abnormal conditioning of the main circuit such as would be insufficient to cause loss of the code signal of 25 such main station once it were set in operation.

It is a further object to provide, in such a signaling system, means whereby signal formulation in the associated main circuit, irrespective of whether occurring under normal or emergency 30 conditions, will not be interrupted or impaired resultant from actuation of any sub-station or stations.

It is a further object to provide, in such signaling systems, construction and arrangement of parts such that assurance of responsive operation of an associated main station will not be impaired in the event that a plurality of sub-stations is actuated at or about the same time.

In the use of prior forms of shunt type auxiliary systems, there have been instances in which an objectionable number of needless signals have resulted from accidental auxiliary loop breakage.

It is, therefore, a further object of this invention to provide a shunt type system which is susceptible of embodiment in a form and arrangement whereby tripping of auxiliarized or main stations will not result from accidental shunt loop breakage.

The transmission of an objectionable number 50 of needless signals has also been experienced in the use of some shunt type auxiliary systems, particularly where the main line circuit has been subjected to current surges, as from lightning or from accidental contacts with foreign circuits. It is evident that, in such systems, as

heretofore constructed, some part of the main line current flow always passes through the winding of the tripping magnet, although the major portion may be divided out, pursuant to Ohm's Law, and pass through the closed shunt loop. Assuming, however, that the usual main line current flow is on the order of 0.1 ampere, and that the trip magnet is made dependably operable at 0.06 ampere, in order to provide a factor of safety (as is common practice), and that the relative resistances of the magnet winding and of the shunt loop current paths is such that but one-fifth, or even one-tenth, of the main line current flow reaches the winding of the tripping magnet while the shunt loop is intact (which would be 0.02 or 0.01 ampere at normal main current flow), should a surge momentarily increase the main line current flow to 0.03 or 0.06 ampere or more, in the respective circumstances, effective energization of the tripping magnet would result.

It is, therefore, another important object of this invention to provide a shunt type auxiliary system which may be embodied in a form such that tripping of master or auxiliarized main line stations will not result from current surges in the main line circuit.

Inasmuch as attainment of the object just stated, in accordance with this invention, involves the utilization of a master station tripping magnet having a self-neutralizing winding, it is a subsidiary object of this invention to devise a method of applying such a winding whereby minimum opportunity will be afforded for development of what may be termed "anomalous poles" such as are likely to become significant when opposing sectional windings extend along substantial portions of the length of an electromagnet core and are subjected to comparatively large current flow, with resultant development of a free pole or poles of such strength as to cause response of associated armature.

In order that desired results may be obtained when this invention is utilized in connection with signaling systems in which no signaling electromotive force is normally (or, in some instances, at any time) maintained between the main signaling circuit and the earth or any other common return conductor; and/or where, for any reason, it is deemed objectionable to provide electrical connection between the main signaling circuit and conductors connecting sub-stations either at particular times or at all times: It is a still further purpose of this invention to provide a system in which all desired results may be obtained through use of sub-stations (with or without answer back equipment) connected with the master station through conductors which may at all times be isolated from the main circuit, or which may be associated at times with the main circuit, for obtaining desired electrical test and supervision therefrom, and may at other times be completely isolated from the main circuit in a very simple manner, all without impairing the functional features of the system other than in respect to the loss of such main circuit test and supervision, and (as by providing magneto generators at sub-stations) without thereby incurring the use of primary or secondary batteries or other forms of current supply mechanism needing periodic replenishment or supervision or subject to extraneous suspension or disconnection.

In meeting practical operating conditions, many instances are found in which it may be deemed advantageous to minimize the number of required conductors, or otherwise to simplify or 5 to delete certain features of this invention, notwithstanding resultant loss of one or more functional results deemed highly important under other circumstances.

It is, therefore, a still further object of this 10 invention to provide a system which is suited for various modifications and simplifications, involving deletion of various structural features and functions, whereby to meet differing local conditions and requirements.

15 Other objects, together with their inherent advantages, will be in part obvious and in part specifically pointed out in connection with the ensuing description of the illustrated embodiments of this invention.

20 In applying this invention to signaling systems employing normally closed main line circuits having a constantly available emergency signaling path between such circuits and the ground or some other common return conductor: Main

25 stations are provided having tripping magnets which are subject to energization by normal main line current flow; loops are associated with such magnets for maintaining them in normally de-energized conditioning; sub-stations are connected by these loops, each having mechanism which may be manually or otherwise actuated or set in action for effecting a series of two or more changes in loop conditioning for the purpose of causing energization of an associated main station trip magnet.

Such sub-station mechanism is of a character such that its first step of operation serves to alter the conditioning of associated loop or loops 40 in such manner that the associated trip magnet will be immediately energized if normal main line current flow is then available therefor, and such that, if the normal main line current path is then interrupted because a code signal is in course of formulation therein, such magnet will 45 be energized during the next ensuing closure incident to the formulation of such code signal.

Ensuing action or actuation of such sub-station mechanism establishes a connection or connections, between associated loop or loops and the ground or other common return conductor, whereby trip magnet energization will be effected in the event that the main line circuit is broken at one side or the other of the main station, and/or in the event that the main station is short-circuited.

Tripping mechanism associated with and for response to energization of each trip magnet, sets in action associated main line signal formulating mechanism.

60 Said tripping mechanism, in acting, also completely disconnects sub-station loop conductors from the main line circuit, besides excluding the resistance of the tripping magnet winding from the main line circuit.

65 In accordance with one aspect of this invention, the sub-station mechanism may be made responsive to a plurality of actuating steps separated by time intervals governed by the person 70 or extraneous agency which actuates the sub-station. However, when circumstances are such as seem likely to be most frequently found, the sub-station mechanism will include means for measuring the time between the first revision of loop conditioning and later revision or revisions,

so that such time will be adequate to prevent mutilation of code signals which are in course of transmission. Under some conditions a time merely longer than any between closures within code signals but less than that between repetitions or "rounds" may be deemed preferable, but under many other conditions it will be deemed expedient that such time shall be greater than the longest open circuit interval incident to the formulation of any code signal in the main circuit.

Need for delay between actuating steps of sub-stations, and need for action of the trip mechanism to disconnect the sub-station loop when acting in response to the first actuating step of a sub-station, as just referred to, arises from the fact that unintended signaling impulses would otherwise occur in the main line circuit; which impulses would be likely to cause serious errors in the interpretation of signals.

If, however, each sub-station acts to apply its ground connection only after a time longer than any open circuit interval in any main line signal, throughout which time it has conditioned its loop to render the trip mechanism of its associated master station responsive to main circuit energization, and such trip mechanism, when it so acts, isolates such loop from the main line, such isolation will always occur before ground connection application, when any sub-station is activated during the formulation of any signal in the main circuit of its associated master station.

If the master station formulates its code signal but once, it may be sufficient to delay application of the ground connection for a time longer than any between impulses within code signals; but if such code signal is repeated one or more times, it becomes important that such delay time shall be longer than that between the last impulse of any one round and the first impulse of the next succeeding round.

Where operating circumstances are such that it is desired that a presignal stroke shall be formulated when a master station has been set in action through utilization of an emergency current path, said mechanism effects such loop conductor disconnection immediately following effective tripping magnet energization; when, however, operating circumstances are such that a presignal stroke is not desired, mechanism is provided whereby such disconnection will occur only after the main line signal formulating mechanism has proceeded in its activity to a stage for bringing emergency circuit conditioning into effect.

An embodiment of this invention which is specially suited to operating conditions such that tripping magnet resistance is normally excluded from the main line current path and to conditions such that it is desirable to minimize opportunity for unintended energization for the tripping magnet resultant from abnormal main line current surges, provides a tripping magnet winding so applied and connected that normal main line current flow through one part of said winding will neutralize that through another part.

Portions of said winding are applied in substantially turn-by-turn, side-by-side relationship, in order that opportunity for effective excitation may be avoided, even during extraordinarily great current flow in portions of said winding which should neutralize each other, except when conditions are such that current flow

in a portion of said winding is extraneously caused to be in opposite direction or substantially different in intensity from that in another portion thereof.

- 5 Shunt loops are associated with said winding parts, respectively, and sub-station contacts are so connected in said loops that the first step of the actuation of the contacts of any sub-station will interrupt one of said loops, and, following 10 the lapse of a predetermined time such as aforementioned, the other loop will be interrupted and one of the ends of at least one of said loops will be connected to the ground or other common return conductor; the loop end or ends 15 thus grounded being such as communicate with portions of the tripping magnet winding which are reached by main line current flow only after traversing one, or the other, or both of the aforementioned parts of said windings.
- 20 For use under operating conditions such that it is deemed highly important to avoid unintended trip magnet energization resultant from sub-station loop breakage, and such that constant inclusion of the resistances of trip magnet winding 25 portions and of the sub-station loops in the main line current path is not deemed objectionable, an embodiment of this invention may be employed which provides a differentially wound trip magnet, such as that just referred to, the winding portions 30 of which are correspondingly associated with the main line current path, except that one of the sub-station loops is serially connected between one side of the main circuit and one of the trip magnet winding portions and a second sub-station 35 loop is connected between such of the winding portion ends as are reached from the main circuit only after traversing one or the other of said portions.

- The sub-station contacts associated with these 40 loops are so arranged that, in acting, they will initially interconnect the loops (thus substantially short-circuiting one winding) and thereafter will connect the ground or other common return conductor to the loop which interconnects the two 45 winding portions, and will terminate the initial connection between the two loops.

- For operating conditions such that it is deemed more important to decrease the number of the 50 sub-station loop conductors from that required for the embodiments of this invention just described than to minimize opportunities for unintended energization of the trip magnet resultant from main line current surges, an embodiment of this invention may be utilized in which a trip magnet having a single winding is normally shunted by a sub-station loop, and sub-station mechanisms interrupt such loop incident to the first step of actuation, and thereafter establish a connection to the ground or to a common return 55 conductor, first with one and then with the other of the ends of the interrupted loop, maintaining the connection with one of such ends until it has been established with the other.

- In still another embodiment of this invention, the sub-station mechanism, instead of establishing connections alternatively with one and the other of the sub-station loop ends, establishes such connection intermediate the ends of an 60 asymmetric conductor so associated with the loop as to oppose the main line current flow in a direction such as would shunt the trip magnet winding.

- For utilization in connection with signaling systems which do not provide a constantly available emergency signaling path between a main

signaling circuit and the ground or some other common return conductor, and/or which do not maintain constant current flow in the main circuit path available for energization of a tripping magnet, an embodiment of this invention may be utilized in which sub-stations have normally short circuited magneto generators or other means for causing current flow in the sub-station loop such as will effectively energize the main station tripping magnet.

In the ensuing description and, more particularly, throughout the appended claims, wherever reference is made to "interruption" or to "functionally interrupting" of current paths which associate sub-station mechanism with a signaling or tripping mechanism electromagnet, it should be understood that the meaning denoted by such terms is intended to be inclusive of an increase in resistance of functionally significant extent; and wherever reference is made to "increasing the resistance" of any such path, the meaning denoted by this term is intended, insofar as the context permits, to be inclusive of interruption of such path.

Other characteristics of this invention, as well as certain more detailed features thereof, are shown by the accompanying drawings and set forth in the following detailed descriptions. It should be understood, however, that the embodiments illustrated, though practical, are by no means the only embodiments which this invention may assume, wherefore this invention is not confined to any strict conformity with the showing of the drawings, but may be changed and modified in various ways so long as such changes and modifications make no material departure from the salient features of this invention, as set forth in the appended claims.

In the accompanying drawings:

Figure 1 illustrates schematically and diagrammatically an embodiment of this invention believed to be suited for many practical situations;

Fig. 1A is a simplified "across the line" circuit diagram of the system of Fig. 1;

Fig. 2 shows a modified form of the mechanism of sub-station S¹ of Fig. 1;

Fig. 3 shows a modified form of the contact controlling mechanism of Fig. 2;

Figs. 4 and 5 show modifications of certain portions of the mechanism of sub-station S² of Fig. 1;

Figs. 6, 7, 8 and 9 show modifications of the system of Fig. 1 for meeting various operating conditions;

Fig. 10 shows a modification of Fig. 8 in which the auxiliary loop may, at times, be connected to the main circuit for supervision;

Fig. 11 shows another modification of Fig. 8 in which the auxiliary loop is separate and independent of the main circuit; and

Fig. 12 shows a modification to be referred to, of the master station of Fig. 1.

Circuit arrangement of Fig. 1

The embodiment of this invention schematically indicated in Fig. 1 comprises signal responsive and current supply equipment generally indicated at R, a master box signal initiating station at M, other initiating stations B', B'', and auxiliary or sub-stations S¹, S², with associated answer backs A¹, A².

For convenience, the equipment R will be at times referred to as the "central office." This equipment includes a normally effective battery NB, a ground or common return path battery GB, 75

a line signal manifesting instrument LI, manifesting instruments EI and GI respectively associated with rectifying units IR'' and IR', all arranged substantially in accordance with the teachings of my Patent No. 2,034,017, dated March 17, 1936.

It will be readily understood by those skilled in this art that other arrangements of current supply mechanism and responsive instruments may 10 be substituted for that indicated at R, such, for example, as disclosed by my Patent No. 2,018,656, dated Oct. 29, 1935. If, however, the arrangement of current supply mechanism is such that an alternating electromotive force is developed 15 under any circumstances for signaling purposes between the line circuit and the ground, certain modifications should be made in other portions of the disclosed system, as will be hereinafter more fully pointed out.

20 The conductors 21, 23, 25 and 27 serially connect the station B', master station M and station B'' between instrument LI and the parallel current paths including the instruments EI and GI.

25 The master station M comprises code signal formulating mechanism 31, which may, preferably, be constructed substantially in accordance with my Patent 1,999,859, dated April 30, 1935; although many of the objects of this invention 30 may be attained through the use of "interfering" formulating mechanism which applies a ground connection during each signaling closure, such, for example, as indicated in my Patent 1,528,596, dated March 3, 1925.

35 The relays 41 and 43 are serially included in the main signaling circuit at respective sides of the formulating mechanism 31. (See also Fig. 1A.) In order to meet many of the conditions found in practical service, it is desirable that a

40 normally closed shunt current path should be provided around these relays, such shunt path to be interrupted during activity of the mechanism 31. The contacts 45 are shown as controlling a shunt around these relays as well as 45 around the formulating mechanism 31. These contacts may be controlled in a manner analogous to that disclosed in my aforesaid Patent No. 1,999,859 for the control of the so-called "train shunt" contacts 61, 63 and 81 of said patent.

50 The trip magnet 51 is provided for causing operation of the signal formulating mechanism 31 responsive to actuation of auxiliary or sub-stations associated therewith. In-as-much as the details of this trip mechanism, aside from the 55 electromagnet structure, form no part of a broad aspect of this invention, such mechanism is merely here indicated in a simple schematic manner. Those skilled in this art are doubtless familiar with tripping mechanisms suitable for use in systems such as that indicated in Fig. 1, an example of such prior mechanisms being disclosed in patent to N. H. Suren, No. 1,575,947, dated March 9, 1926.

The trip magnet 51 has neutralizing differential windings so associated with the main circuit that normal current flow from said circuit will pass serially therethrough in such relative directions as will not cause effective energization of this magnet; and so that if one of said windings 70 is substantially short-circuited and there is normal main line current flow through the other winding, said magnet will be effectively energized. If the nature of the mechanism for supplying current to this magnet is such that it may, under any circumstances, be subjected to alter-

nating current excitation, it should be of such type as to be effectively energized thereby.

Although the drawings indicate, as a matter of convenient illustration, that the windings of magnet 51 may be applied in two distinct coils to separate portions of the core, I have found that best results are obtained if these windings are simultaneously applied in parallel convolutions, turn by turn; or at least, first a full layer of one and then of the other.

If actually applied to different portions of the core, abnormally large current flow in both windings is liable to result in development of an intermediate or anomalous pole between the windings, and of a strong free pole adjacent to the armature, and thus result in unintended tripping of the master station.

An end of one winding of the magnet 51 is connected to the main line conductor 23 and, through the normally closed contacts 65, to an end of the normally closed shunt loop 55. An end of the other winding is connected with main line conductor 25 through relays 43, 41, and mechanism 31 (as well as, alternatively, through shunt contacts 45, when closed). Said second named winding end is also connected, through normally closed contacts 67, with an end of the normally closed shunt loop 57. The remaining ends of these windings are connected together and are further connected through contacts 64 with terminal 53. The remaining ends of shunt loops 55 and 57 are also connected to terminal 53 through various contacts presently to be described.

From the foregoing it will be observed that these shunt loops normally exclude substantially all of the resistance of the windings of the magnet 51 from the main circuit current path and, furthermore, the arrangement is such that should there develop in the main circuit a surge of current of such magnitude that the portion passing through the windings of the magnet 51 (due to shunt loop resistance) would be sufficient to cause unintended tripping of the master station, where the magnet of the single winding type heretofore employed in master station trip mechanisms, the magnet 51 would not be thereby effectively energized, because current flow in one of its windings would still serve to neutralize that in the other of said windings.

Furthermore, because of the arrangement just described, the magnet 51 may be effectively energized by grounding the terminal 53 during shunt loop open circuiting, either in the event that the main circuit is broken at one side or the other of said magnet or in the event that said magnet is short-circuited, as for example, by an accidental connection between conductors 23 and 25.

An armature 52 normally restrains actuation of tripping mechanism generally indicated at 33, 35, and is responsive to effective energization of said magnet 51 for causing the formulating mechanism 31 to be set into action and for moving contacts 47, 49, 64, 65, 66 and 67 from their normal positions, as will be hereinafter more fully explained.

Auxiliary or sub-stations S¹ and S² are equipped with contacts which normally maintain the continuity of both of the shunt loops, and each station has mechanism (which will be presently described in greater detail) which mechanisms, in operating, first act to interrupt one of the shunt loops and, after a suitable delay, act to interrupt the other of said loops and

ground the portions of said loops which are associated with the terminal 53.

Although it is immaterial which of the shunt loops is initially interrupted by the sub-stations 5 of any group, all sub-stations of a given system should be so connected that each will initially break the same one of these loops. Otherwise, if two sub-stations were simultaneously operated and one broke one loop and the other the remaining loop, both windings of the trip magnet 51 would be simultaneously subjected to current flow, so that there would be no effective energization. Correspondingly, it will be evident that all stations should be so connected that they 15 will apply their ground connections to the portions of both of the loops leading toward terminal 53.

At each of these sub-stations, contacts 71 and 20 77 are connected with conductors of loops 55 and 57 which lead toward the free or extreme ends 25 of the windings of magnet 51; while contacts 73 and 75 are connected with conductors of these loops which lead toward terminal 53; and contact 79 is connected with the ground.

An inverted L-shaped extension 63 is carried by the contact 73 for at times engaging the contact 75, as will be hereinafter more fully explained.

Under normal conditions, contact 73 rests 30 against contact 71, and contact 75 rests against contact 77; contact 79 being spaced away from contact 73.

During operation of either of the sub-station contact actuating mechanisms, its associated contact 73 is moved away from contact 71 but is not, at first, moved far enough to engage its contact 79 or to carry its extension 63 into engagement with its contact 75.

Thereafter, further movement is imparted to its contact 73, carrying it into engagement with its contact 79, and carrying its extension 63 into engagement with its contact 75 so as to move the latter away from its contact 77, following action of such actuating mechanism in measuring the elapse of a predetermined time, which time, 45 should, for many operating conditions, be greater than any open circuit interval incident to the formulation of any signal in the main circuit.

The novel form of answer back signaling 50 equipment (comprising, for example in Fig. 1, the loop 91, battery 93, relays 41 and 43, signals A¹ and A², and contacts 85) is indicated in the drawings and herein rather briefly described in connection with the invention defined by the appended claims, for the purpose of emphasizing 55 certain of the novel results obtainable through the use of this invention; but such answer back equipment is more fully described and is claimed in an application divisional herefrom, filed January 31, 1941, Serial No. 376,720.

The answer back loop 91 serially includes the auxiliary sub-stations S¹, S², and a current source herein indicated as the battery 93.

The ends of the loop 91 are connected to the 60 normally open contacts of the relays 41 and 43 in such manner that the energization of either of these relays will complete the current path through said loop.

One or more general warning signals may be 65 connected for response to the loop 91 as, for example, the warning bell 95.

In order that answer back signals will be manifested only at actuated sub-stations, each sub-station is shown as having a pair of normally closed contacts 85, through which the cur-

rent path of the loop 91 is normally maintained. Should it be desired that answer back equipment should act at stations other than those from which calls have been sent, contacts 85 should be maintained in open position at, or should be omitted from such stations.

Answer back signal responsive devices of desired type (typified by the tap bells 97 of answer backs A¹, A², shown associated with the sub-stations S¹ and S² respectively) may be associated with the various sub-stations in such manner as to be responsive to the answer back loop 91, during actuated conditioning of the respectively associated contacts 85.

Supplemental to the tap bell 97 of answer back A², there is shown a lamp 99 and buzzer 101 for operation from the current source 103 during actuated positioning of the hammer of the bell 97.

Actuating mechanism of sub-station S¹

The novel form of sub-station contact actuating mechanism or circuit controller for signaling means indicated at sub-station S¹ of Fig. 1, and in Figs. 2 and 3, will be herein briefly described in order to facilitate a complete understanding of the invention defined by the appended claims, but this circuit controller is more fully described and is claimed in an application, divisional herefrom, filed January 16, 1941, Serial No. 374,656, now Patent No. 2,301,924, dated November 17, 1942.

The mechanism of sub-station S¹ comprises the collapsible bellows 111, a lever 113 movable for compressing said bellows responsive to the spring 115 and for rocking the contact actuating lever 125, a trigger 117 for engaging said lever 113 to prevent such movement and subject to disengagement therefrom by manual or other actuation, an expandible chamber 119 connecting with the interior of said bellows through a restricted passage 121 and having a wall 123 movable responsive to the expansion of said chamber for swinging the finger 127 upon attainment of predetermined pressure within said chamber. The contact 73 is subject to partial actuation by said lever 125 and to supplemental actuation together with contacts 75 and 85, responsive to said finger 127.

Means should be provided, such as the spring 129, for assuring extended conditioning of the bellows 111 while the lever 113 is retained by the trigger 117.

The bellows 111 and the chamber 119 may contain air or other fluid, and the various parts should be so relatively proportioned that, when the trigger 117 has been disengaged from the lever 113, the spring 115 will act through said lever to compress the fluid in said bellows 111 and thereby to slowly force a portion of such fluid through the passage 121, whereby to build up pressure in the chamber 119 sufficient to cause the wall 123 to act through the finger 127 to impart suitable actuation to the contacts associated therewith.

The restriction of the passage 121 should be such that, from the commencement of the compression of the bellows 111 to the attainment of a pressure in the chamber 119 such as will cause full actuation of the associated contacts as hereinafter more fully explained, there will elapse a predetermined time. For many service conditions, this time should be longer than the longest open circuit interval incident to any signal in the main circuit.

The lever 125 is so associated with the lever

113 and the contact 73 that, when said lever 113 is moved by the spring 115 to the position which it assumes when released from the trigger 117, the contact 73 will be moved away from the contact 71, and thereby interrupt current flow in the shunt loop 55, for reasons heretofore more fully indicated.

The finger 127 is so associated with the wall 123 and with the contact 73 that when said wall 10 moves from its normal position (after the contact 73 has been actuated by the lever 125, as already explained), the contact 73 will be brought into engagement with the contact 79 (thus grounding one end of loop 55, as already described) and so that the same or further movement of said contact 73, acting through the extension 83, will move contact 75 away from contact 71, thereby breaking the loop 57 and connecting one end thereof to the earth. Such movement of the finger 127 will also separate contacts 85, if used.

In order that contact 73 will be firmly actuated, and transient or chattering connections may be avoided, it is desirable that the steps of actuation of said contact shall be effected quickly by the finger 127. To this end, the free end of said finger is shown as having notches formed therein, and the spring pressed dog 131 so engages said notches that said finger will not move from its normal to its intermediate position until there is sufficient pressure in the chamber 119 to assure practically instantaneous or "snap" action, and correspondingly as to movement from intermediate to fully abnormal position.

Restoration of the mechanism of sub-station S¹ may be effected, after it has acted following disengagement of the trigger 117 from the lever 113, by moving the lever 113 against the urge of the spring 115, and effecting reengagement thereof by the trigger 117; whereupon the spring 129 will expand the bellows 111, thus creating a relative vacuum in bellows 111 such as will cause the fluid which has been forced into the chamber 119 to return into said bellows, whereupon the wall 123 will be restored to its normal position, and (the lever 125 having been moved away from the contact 73 when the lever 113 was restored) the various contacts associated with the finger 127 will return to normal positioning.

If operating conditions are such that it is found desirable to distinctively provide for a third operating step resultant from compression of bellows such as 111, this may be accomplished as indicated in Fig. 2 by use of a supplemental chamber 219', the interior of which is connected with that of the chamber 219 through the passage 233, and through passage 221 with collapsible bellows 211, which correspond with the bellows 111 of Fig. 1.

The use of such a supplemental chamber will cause a distinctive added step of actuation to be imparted to the contact 73, whereby said contact will be first moved away from the contact 71, either by the lever 113 acting through the lever 125 or resultant from initial movement of the wall 223 acting through the finger 227, and, thereafter, following a suitable delay, said contact 73 will be moved into engagement with contact 79 when the wall 223 of the chamber 219 is moved to its fully actuated position. Still later, following a second suitable delay, the finger 235 will be moved by the altered positioning of the wall 223' of the chamber 219' to cause the contact 73 to carry the extension 83 into en-

gagement with the contact 75 and thereby move said contact 75 away from the contact 77.

Likewise, as indicated in Fig. 3, the finger 335 (corresponding to the finger 235 of Fig. 2) may be utilized for neutralizing the effect of the actuation of the contact 73 by the finger 327. Said finger 327 is similar in action to finger 227 of Fig. 2, and is pivotally attached, at 328, to the free end of finger carrier 327'; which carrier is pivotally supported at 326. With the arrangement shown, after the contacts 73 and 75 have been connected to the contact 79 for a desired time (responsive to movement of the wall 323 away from its normal position) subsequent movement of the wall 323' will result in said contact 73 being permitted to move away from the contact 79 and such movement will carry the extension 83 away from the contact 75, permitting said contact 75 to reengage the contact 77, whereupon shunt loop 57 will be closed, shunt loop 55 will remain open, and the ground connection through contact 79 will be isolated from both loops.

Those skilled in this art will recognize advantage of ultimately disconnecting the ground connection at an operated sub-station when such station is utilized in connection with a well-known form of master station tripping mechanism, which mechanism is so arranged that it may be partially reset for the purpose of determining if the sub-station loop current paths have been restored to normal condition (as at all actuated sub-stations), and preventing a completion of restoration of the main station in the absence of normal loop conditioning.

It is evident that, in the absence of partial restoration of sub-station contact relationship such as just described, both shunt loops would remain open, and the trip magnet would not be energized upon such partial restoration of the trip mechanism, because resultant current flow in one of its windings would neutralize that in the other winding.

It is further evident that, unless the sub-station ground connection is first disconnected, such partial restoration of the tripping mechanism of the main station will result in temporarily grounding the main circuit and thereby causing a central office signal manifestation which might be objectionable under certain operating conditions, particularly if the trip mechanism must be permitted to return to fully tripped condition responsive to the rendering effective of such a ground connection incident to partial restoration thereof.

Actuating mechanism of sub-station S²

As an example of means, along lines of prior art mechanisms, which may be utilized for effecting actuation of contacts of sub-stations in accordance with the broader aspects of this invention, reference is made to the sub-station mechanism which is more or less schematically indicated in Fig. 1 at S², disclosing clock-work mechanism whereby a predetermined series of changes in circuit conditioning may be effected in a sequence which is timed suitably for the purposes of this invention.

The mechanism at S² is arranged for response to manual actuation of the handle 151, which is carried by the shaft 159, together with the notched disk 161 and the escape wheel 163, each for movement independently of the others.

A spring 165 has its respective ends connected to said handle and to said disk 161, for tension-

ing responsive to counterclockwise rotation of said handle around its pivot 159, so as to urge like rotation of said disk.

A segment 167 moves with said handle, and a face 169 of said segment is disposed in the path of the pin 171, which is carried by the disk 161, for limiting the extent of the rotation of said disk responsive to the spring 165.

The escape wheel 163 is driven by the disk 161, acting through the spring pressed click 173, and the escapement 175 governs the speed of rotation of said wheel, and therefore of the counter clockwise rotation of said disk.

The stops 177 and 179 are situated in the path of the handle 151, for limiting its angular movement to slightly more than that between adjacent notches in the disk 161.

The latch 181 is pivoted at 183, and the free end of said latch so co-operates with the segment 167 as to be supported thereby other than when said segment is in the position which it assumes when the handle 151 is in or near contact with the lower stop 179, and, at such times, said latch may be moved by the spring 185 into the path of said segment and thereby retain such positioning of said segment. A handle 187 is associated with said latch to facilitate manual withdrawal thereof from the path of said segment.

A flexible brake 189 co-operates with the escapement 175 and is governed by the latch 181, so that when said latch is supported by the segment 167 said brake will prevent operation of said escapement, and so that movement of said latch into the path of said segment will free said escapement from said brake.

A finger 191, pivoted at 193, projects into the path of the stud 195 carried by the disk 161; said finger being so formed and positioned with relation to said stud that, as said disk approaches the limit of its counter clockwise rotation, said stud will engage said finger and move it from its normal to an extreme abnormal position.

The flexible contacts 71, 73, 75, 77, 79 and 85 are so associated with each other, with said latch 181 and with said finger 191, that contacts 71, 73, and contacts 75, 77, and contacts 85 are normally engaged; that contacts 71, 73, will be separated whenever said latch 181 is positioned in the path of the segment 167; and that movement of the finger 191 from its normal toward its extreme actuated position will bring contact 73 into engagement with contact 79, and will cause a connection to be established between contacts 83, 75, and final movement of contact 73 by finger 191 will effect separation of contact 75 from contact 77; contacts 85 being meanwhile separated.

As heretofore more fully explained, contacts 71, 73, are intended for serial inclusion in a master-station shunt-loop, contacts 75, 77, for like connection in another such loop, and contact 79 for connection to the ground.

The timing of the rotation of the disk 161, which is effected by the escapement 163, 175, is such that, from the freeing of said escapement when the latch 181 moves into the path of the segment 167 until the stud 195 so moves the finger 191 as to cause a connection to be established between contacts 73 and 79, there will elapse a predetermined time, which, for many service conditions, should be greater than any open circuit interval incident to the formulation of any signal in the main circuit.

From the foregoing it will be noted that, when the mechanism of station S², as just described,

has come to rest, the contacts 73 and 75 will remain connected to the grounding contact 79 and separated from the contacts 71 and 77 which are normally engaged respectively thereby.

As heretofore pointed out, this will result in continued grounding of portions of both of the shunt loops, as well as keeping both of such loops open.

For operating conditions such that it is desirable that the ground connection shall be terminated, and one of the shunt loops closed, before attempt is made to reset the master station, such results may be obtained by substituting the finger 491 of Fig. 4, for the finger 191 of Fig. 1; the portion of the finger 491 which is disposed in the path of stud 195 being so formed and positioned that, after said stud has depressed this finger for desired actuation of the associated contacts, said stud will pass beyond such actuating face before the disc 161 comes to rest, and will therefore permit the finger 491 to move to a position which allows contact 73 to move away from contact 79, thereby incidentally permitting contact 75 to move into engagement with contact 71.

It is evident that with finger 491 formed as shown, and when thus restored after the stud 195 has passed beyond the actuating face thereof, a portion of said finger 491 will be disposed in the restoration path of the stud 195, and must be withdrawn from such path before the disk 161 can be moved to its normal position. A handle 497 is therefore shown on the finger 491, so that said finger may be manually moved to withdraw its obstruction from the path of the stud 195 at the same time that the handle 157 is employed for moving the latch 181 out of the path of the segment 167.

Operation of the station at S², for causing the starting of an associated main station, is accomplished by moving the handle 157 from its normal elevated position (adjacent to stop 177) into engagement with stop 179.

Such movement of the handle 157 will stretch the spring 165 and thereby urge rotation of the disk 161 together with the escape wheel 163, but the escapement 175 will be locked against operation by the brake 189 until said handle has nearly reached the stop 179, when said segment will be withdrawn from the path of the latch 181. Thereupon, the spring 185 will move said latch into the path of said segment, and thereby lock the handle 157 and parts moving therewith from return to their normal position. Such movement of said latch will also cause contact 73 to be moved away from contact 71 and will withdraw the brake 189 from restraint of escapement 175.

The disk 161 will thereupon act through the click 173 to rotate the escape wheel 163, and the escapement 175 will so time such rotation that the stud 195 will not engage the finger 191 (or the finger 491, as the case may be) until the end of a suitable predetermined time, following the movement of contact 73 away from contact 71.

After the stud 195 has engaged the actuating surface of the finger 191, further rotation of the disk 161 will result in movement of the finger 191 such as will accomplish the sequence of contact relationships hereinbefore more fully described; after which, the rotation of the disk 161 will be arrested when the pin 171 overtakes the face 169 of the segment 167, in the position to which it has been moved.

After actuation as just described, the station mechanism can be restored to normal condition by moving the handle 157 into engagement 75

with the stop 177, having first swung the latch 181 out of the path of the segment 167 and, in the instance of a station using finger 491, having swung said finger out of the path of the stud 195.

Such restoration of the handle 157 and of the disk 161 will permit the click 173 to enter the next notch in said disk and—the brake 189 being now in holding relationship with the escapement 175—the various parts will remain in their normal conditioning until the handle 157 is again moved to the stop 179.

For service conditions in which it is desirable that a sub-station similar to that at S² may be caused to act by a force insufficient to move the handle 157 to effect stretching of the spring 165, such mechanism may be converted into a "pre-wound" type by applying thereto the parts indicated in Fig. 5, comprising a latch 581 for co-operation with the segment 167, with an independently moving, associated lever 599 carrying the flexible brake 189 and having an associated arm 599' for actuating contact 73 and for engagement with a trigger 517.

It will be evident that, with these parts, the handle 157 may be moved to the stop 179, and thereby stretch the spring 165, and the latch 581 will engage the segment 167 and retain the parts in such pre-set positioning, while the brake 189 will hold the escapement 175 from operation until the trigger 517 is moved to disengage the free end of the arm 599', which arm will thereupon be moved by the spring 585, so as to withdraw the brake from restraining the escapement 175 and so as to move the contact 73 away from the contact 71, whereupon the various operative steps will occur as already described.

In resetting a station having the parts indicated in Fig. 5, the handle 588 will be used for withdrawing the latch 581 from the path of the segment 167, and such movement of said handle will bring the pin 587 into engagement with the lever 599, causing it to carry the brake 189 into engagement with the escapement 175, while incidentally permitting the contact 73 to move into engagement with the contact 71.

Description of Fig. 6

Should it be desired to utilize an arrangement such that breaks in shunt loops will not cause tripping of the master box, the shunt loop relationship to the tripping magnet, as indicated in Fig. 6, may be utilized in the place of that indicated in Fig. 1.

Pursuant to the arrangement of Fig. 6, the main line current path from the conductor 23 normally includes the contacts 664, 665, the loop conductor 641, a portion of the contact 643, the conductor 645, the contacts 669, one winding of the magnet 51 (see also Fig. 1), the contacts 667, the conductor 647, a portion of the contact 649, the conductor 651, the contacts 668, the other winding of magnet 51, from the remaining end of which latter winding the main line current may pass through other circuit portions in a manner corresponding to that indicated in Fig. 1.

During activated positioning of the contacts 664-669, (as by the arm 33 of Fig. 1), contact 666 provides a current path from contact 664 which by-passes the windings of magnet 51 as well as the loop conductors, after the establishment of which the loop ends are disconnected from the main current path at open contacts 665, 667, 668 and 669.

The sub-station transfer contact 653 normally

engages the contact 643, and the grounding contact 655 is normally spaced away from the contact 653; the arrangement of these contacts being such that, during a first step of actuation of the contact 653 (as by the lever 125 of station S¹ of Fig. 1, or the latch 181 of station S² of Fig. 1) said contact 653 will be brought into engagement with contact 649, and, during ensuing actuation of the contact 653 (as by finger 127 of station S¹ of Fig. 1 or finger 191 of station S² of Fig. 1) said contact 653 will be moved away from contact 643 and against contact 655.

During simultaneous engagement of contacts 643, 653 and 649, as just described, one of the windings of magnet 51 is thereby short-circuited; whereupon, normal current flow through the other winding will cause effective energization of said magnet with the resultant tripping of the signal formulating mechanism, providing that the main line current path is then effective.

After contact 653 has been moved against contact 655 and away from contact 643, current may flow through either of the windings of the magnet 51 and through contacts 649, 653, 655 to the ground or other common return conductor, in accordance with possible broken main line conditions at one side or the other of the magnet 51, and current may flow cooperatively to ground through both of said windings if the portions of the main line circuit at respective sides of this magnet provide a short circuit around it, as neither of its windings will then be short circuited between contacts 643, 649.

It should be understood that such ensuing movement of the contact 653, whereby a ground connection is established, will be effected only at the end of a suitable time, such as previously referred to, following the aforesaid first step.

Results characterizing use of the loop arrangement of Fig. 6 may be summarized as follows:

Both windings of the tripping magnet 51 and both sub-station loops and their associated contacts are under constant supervisory test from the main circuit.

A break in either loop or its disconnection from respectively associated contacts 643, 649, opens the main circuit, but does not cause unintended tripping of the main station or render the magnet 51 unresponsive to application of a ground connection incident to actuation of an associated sub-station.

Accidental grounding of the loop 641, 643, 645, gives a central office indication but does not cause unintended starting of the main station.

Accidental grounding of the loop 647, 649, 651, will give a central office indication, and will be likely to cause unintended starting of the main station, depending upon the resultant degree of unbalancing of normal current flow in the windings of magnet 51.

It will be noted that, inasmuch as the excitation of magnet 51 which might result from current flow in one of its windings is neutralized by that of like current flow in the other of its windings, current surges in the main line path will not cause unintended tripping of the main station formulating mechanism during normal conditioning of the sub-station loops.

It will also be understood that the arrangement of Fig. 6 is not suitable for use in situations where the constant inclusion in the main line current path of the resistances of both windings of the magnet 51, as well as those of the sub-station loops, would be objectionable.

Description of Fig. 7

Where operating conditions are such that it is deemed inessential either that energization of the trip magnet will be assured in the event that such magnet is short circuited, or that no such energization will result from current surges in the main line, a single shunt loop arrangement, such as indicated in Fig. 7, may be substituted for double loop arrangements such as are indicated in Figs. 1 and 6.

Sub-stations S¹ and S², as here shown, have asymmetric conductors 769 associated as herein-after more fully explained, so as to cause energization of their trip magnets during broken main line condition by a single application of the ground connection, while the arrangement of station S³ is such that application of the ground connection is needed, first to one and then to the other of the severed loop ends.

When asymmetric conductors are used, as indicated at stations S¹ and S², the central office current source should be of such character that the direction of current flow will not be other than normal, in any portion of the main line circuit, resultant from application of a ground connection thereto. Otherwise, application of a ground connection intermediate the ends of an asymmetric conductor such as 769, will, under certain conditions, fail to result in effective energization of the associated tripping magnet. For this reason, when asymmetric conductors are employed as indicated in Fig. 7, a form of current supply such, for example, as that disclosed in applicant's aforementioned prior Patent No. 2,018,656, should be substituted in place of forms having characteristics such as those of the current supply indicated in Figs. 1 and 1A.

In the interests of simplicity, main station loop cut off contacts, answer back facilities and various other features, the general nature of which is sufficiently illustrated by Figs. 1 and 6, are omitted from Fig. 7, in which contacts of the three auxiliary stations S¹, S², S³ are shown serially included in loop 751.

In the instance of station S¹, sub-station contact operating mechanism (which may be such as that indicated in stations S¹ or S² of Fig. 1) will first open the contacts 759 (as by the lever 125 of Fig. 1) and will, a suitable time thereafter, close the contacts 765 (as by the finger 127 of Fig. 1).

In the instance of station S², the switch 759' may be first opened (manually or otherwise) and, a suitable time thereafter, switch 765' may be closed. For certain classes of service where trained persons may be relied upon for actuating substations, and particularly where answer back signals are available, manual actuation of stations such as S² might be relied upon; the operator being instructed to first actuate sufficiently to open switch 759' and, thereafter, if the answer back signal does not indicate within a reasonable time that the main station is formulating its code in a then effective current path (as hereinbefore more fully explained) the operator can further actuate the mechanism to effect closure of switch 765'.

In the instance of station S³, operating mechanism similar to such as contemplated for station S¹ may be employed for first opening the contacts 759 thereat, and, a suitable time thereafter, withdrawing support of the contact 781 (as by movement of the finger 127 of Fig. 1) permitting said contact 781 to move into engagement with contact 783 and thereby ground one end

of the shunt loop which has already been broken between contacts 759. Ensuing movement, as of the finger 127, thereafter moving contact 783 into engagement with the one of the contacts 759 which is connected to the other end of the shunt loop, and further movement of said contact 783 carrying it away from contact 781, thereby grounding the other end of the shunt loop, while not disconnecting the ground from one end before it is connected to the other end, so as to avoid possible formulation of an extra signaling impulse in the main line circuit.

With the arrangement of Fig. 7, it is evident that, so long as the loop contacts 759 are closed at the associated sub-stations, the normal shunted condition of the tripping magnet 751 will be maintained. Upon breaking this loop, as by opening at either of said contacts 759 or at switch 759', the shunt around the tripping magnet will be broken and, if normal energizing current is then available in the main circuit, said magnet will be energized and will cause tripping of the associated main station formulating mechanism.

If the main circuit is open on any such occasion, it is evident that the breaking of the shunt loop will not of itself cause energization of the tripping magnet. However, in the instances of stations S⁷¹ and S⁷², it will be seen that the ground connection is applied intermediate the ends of the asymmetric conductor 769, (which conductor bridges the break occasioned by opening the contacts 759 of S⁷¹ or of switch 759' of S⁷²) in such relationship to the direction of current flow in the main line that said conductor 769 will prevent significant main line current flow therethrough other than in such direction as will be effective after such current has traversed the winding of the trip magnet 751; hence, if the main circuit is open at either side of said magnet, current from the remaining side of the main circuit may only reach the ground connection of an actuated station S⁷¹ or S⁷² after having energized the tripping magnet 751.

Similarly, in the instance of station S⁷³, grounding of first one shunt loop end and then of the other, assures effective energization of the trip magnet if there is a suitable electromotive force between either terminal of said magnet and the ground.

Use of asymmetric conductor arrangements, such as indicated for stations S⁷¹ and S⁷², is advantageous when sub-station structure is not such as to provide for application of a ground connection, independently, first to one and then to the other end of a severed sub-station loop.

In the use of forms of this invention in which the tripping magnet has a single winding shunted by a sub-station loop, as in Fig. 7, application of the sub-station ground connection intermediate the ends of an asymmetric conductor, as indicated at 769, avoids occasion for providing mechanism for separately grounding first one and then the other shunt loop end, as is contemplated by the arrangement indicated at station S⁷³.

The use of asymmetric conductors is correspondingly desirable in sub-stations (such, for example, as station S⁷²) in which all shunt loop alterations are, or may possibly be, effected simultaneously.

Description of Figs. 8, 9, 10, and 11

In the instances of signaling systems in which no electromotive force is applied from the central office between the main line circuit and the

earth, other than during broken circuit conditions, systems arranged in accordance with Figs. 1, 6 and 7 would fail to effect tripping of the master station in the event that it becomes short circuited.

To meet these and certain other special circumstances, arrangements such as those indicated in Figs. 8 and 9 may be utilized.

Referring to Fig. 8, the trip magnet 851 may be associated with the main circuit in the usual manner, or, if circumstances are such that it is deemed unnecessary to maintain main line circuit constant test of the shunt loop from the central office, or should it be deemed undesirable that there be any electrical connection between the main current path and conductors which connect sub-stations, the winding of this trip magnet may be normally isolated from the main circuit; as by use of the cut-off switch 1092 of Fig. 10, or by complete omission of such an interconnection, as indicated in Fig. 11.

The terminals of said trip magnet 851 are connected to the contacts 853 and 855, respectively, and contact 857 normally engages contact 853, while contact 859 normally engages 855.

The ends of the shunt loop 867 are connected to the contacts 857 and 859, respectively, said contacts being separable by main station mechanism in a manner analogous to the operability of contacts 64, 65 and 67 of Fig. 1.

In each auxiliary or sub-station there is provided a normally shunted magneto generator 871, with means 873 responsive to actuation of the generator for opening its shunt in a well known manner.

Such generators should preferably be of comparatively high resistance type, in instances in which the trip magnet 851 is subject to energization from the main line circuit, to the end that adequate energizing current for said magnet will be diverted to flow through the winding thereof when the shunt around any sub-station generator is interrupted.

It will be evident that the actuation of any sub-station generator will cause effective energization of its associated trip magnet 851, even in the absence of current flow in the main circuit. However, a low-resistance accidental short circuit around the winding of the magnet 851 might prevent energization of said magnet responsive to sub-station generator operation. If it is desired to safeguard against such a condition, and to assure effective energization of the magnet 851 even if a short circuit exists between the conductors 23, 25 of the main circuit, a resistance or reactance 865 should be included in the main circuit at one side or the other of the winding of the magnet 851 so as to oppose alternating magneto current flow around the trip magnet.

If it is desired to provide answer back signals for the system of Fig. 8, this can be accomplished by associating the magneto bells 875 with respective sub-stations, which bells may be in series with the respective generators and controlled by the associated generator shunt, as shown, so as to be short circuited when the generator is at rest.

In order that such bells shall sound in a manner which will identify the code signal of the associated main station, a contact 861 is normally spaced away from contact 857 and a contact 863 is normally spaced away from the contact 859 in such respective relationships that, during actuated positioning, contact 857 will engage con-

tact 851 and contact 859 will engage contact 863.

Relays 841 and 843 are controlled from the main circuit in a manner corresponding to that of relays 41 and 43 of Fig. 1, and the normally open contacts of said relays are connected in parallel with each other and between the contacts 861, 863 so that, when the tripping mechanism has acted to move the contacts 857 and 859 from their normal positions, the bell 875 of the active station will sound only during effective closures of the main line circuit at one side, the other, or both sides of the associated signal formulating mechanism. Hence, if operation of the magneto generator is then continued, response of the associated magneto bell will be such as will identify the code number of the associated main station only in the event that such station is transmitting its signal through a then effective main line current path.

It will be noted that, with the arrangement of Fig. 8, the answer back bell is silent if the loop 867 is broken, but that it otherwise sounds throughout actuation of the magneto generator, even in the event that the tripping mechanism of the main station fails to act. Where some of those who might use sub-stations may be untrained in reading code signals, there is danger that such users may assume that any sounding of the answerback bell is a sufficient assurance that a call has been effectively formulated in the main line circuit.

Such an assumption may result in a user of a sub-station failing to employ other means for summoning the fire department at a time when, for any reason, the associated main station fails to formulate its signal in a then effective main line current path. If operating conditions are such that action of this kind is deemed objectionable, the arrangement of Fig. 9 may be substituted for that of Fig. 8.

Referring to Fig. 9, the contacts 953 and 955, the relays 941 and 943, and the generators 971, 971, are similar in operation to the contacts 853 and 855, the relays 841 and 843, and the generators 871, 871, of Fig. 8. Each of said generators having a shunting contact 973 therefor, similar to the contacts 813 of Fig. 8. An answer back loop 969 extends from contact 961, serially through the magneto bells 975, 975 associated with various sub-stations, to one side of the normally open contacts of the relays 941 and 943, the other side of said relay contacts being connected to the contact 963.

Each sub-station magneto generator has a shunt 977 normally short circuiting its associated magneto bell, and each of these shunts moves with the associated shunt 973 so as to break such bell short circuit throughout actuation of the generator.

Operation of any sub-station magneto generator of Fig. 9 will first cause energization of trip magnet 951, with resultant actuation of contacts 957 and 959 so as to transfer the ends of loop 967 from the ends of the winding of magnet 951 to the answer back loop 969 in which the normally open contacts of the relays 941 and 943 are included, in parallel with each other. Consequently, the magneto bell 975 associated with the actuated station will only sound responsive to energizations of one or both of the relays 941, 943.

It will be apparent that interconnection between the main circuit conductors of Fig. 9 may be governed by a switch, such as the switch 1992 of Fig. 10, or that such an interconnection may

be eliminated in a manner such as indicated in Fig. 11.

Normal operation, Fig. 1

Assuming that the main circuit is closed and free from accidental grounds and crosses, and that the mechanisms at the master box M and at the sub-stations S¹, S² are conditioned for intended operation, there will be suitable current flow in the main circuit (see also Fig. 1A) from the battery NB, through instrument LI, conductor 21, station B' and conductor 23 to closed contacts 65 and to a free end of one of the windings of magnet 51. Thence the current will divide and the major portion will traverse said contacts 65, the shunt loop 55 serially including the contacts 71 and 73 of sub-stations S¹ and S², to terminal 53, thence through shunt loop 57 serially including contacts 75 and 77 of sub-stations S¹ and S², to closed contacts 67.

From the contacts 67, current flow will proceed through the shunt contacts 45 to conductor 25, thence through station B'' and conductor 27 and through rectifying unit IR'' and instrument EI to the other terminal of battery NB. There will also be a current path to the remaining free end of the winding of the magnet 51.

Some current will also flow through the windings of magnet 51, due to the resistances of loops 55 and 57, but such current flow in one of said windings will neutralize that in the other, so that there will result no significant energization of said magnet.

Contacts 45 being closed, as already explained, will serve to short circuit the relays 41 and 43 as well as the mechanism 31, thus preventing effective energization of said relays, whose armatures will therefore be in retracted position, whereby to prevent current flow in answer back loop 41. The windings of said relays 41 and 43 being also short circuited by the normally closed contacts 49 and 47, respectively.

Operation now, of contact actuating mechanism of one of the sub-stations S¹, S², may be effected as follows:

Assuming utilization of mechanism such as that at sub-station S¹—depression of the trigger 117 will release the lever 113 which will be moved by the spring 115, and act through the lever 125 to move the contact 73 away from the contact 71 and thereby interrupt current flow in loop 55. The entire current flow of the main circuit will thereupon pass through one of the windings of the magnet 51 while the other of said windings remains substantially short circuited by the loop 57. Thereupon, the magnet 51 will be effectively energized, causing its armature 52 to effect release of the arm 33 which will then move in response to the spring 35.

Such movement of said arm will cause the code signal formulating mechanism to be set in operation or "pulled," with incidental opening of the shunt contacts 45.

Such movement of the arm 33 will also cause opening of the contacts 41, 49, 64, 65 and 67, and will, at the same time, effect closure of the contacts 66.

Such opening of the contacts 64, 65 and 67 will isolate the shunt loops 55, 57 from the main circuit, and such closure of the contacts 66 will short circuit both of the windings of the magnet 51. Such opening of the contacts 41 and 49, supplemental to the opening of the shunt contacts 45, will remove all shunting paths

around the windings of the relays 41 and 43, thus causing effective energization of these relays with resultant closure of their normally open contacts and commencement of current flow in the answer back loop 91, causing energization of the signal 95.

When the lever 113 of the actuated station was moved by its spring 115 as already described, such movement compressed the bellows 111, causing the fluid therein to slowly pass through the passage 121 and build up a pressure in the chamber 119 at such rate that, after the elapse of a time longer than the longest open circuit interval incident to any signal in the main circuit, the finger 127 will be so moved as to carry the contact 73 into engagement with the contact 79, and said finger 127 will further move said contact 73 far enough to bring the extension 83 into engagement with and thereby move the contact 75 away from the contact 71.

Although the ground path associated with the contact 79 will thus be connected to portions of the shunt loops 55 and 57 through the contacts 73, 75, such connection will have no effect upon the magnet 51 or upon the main line current flow, because the loops 55, 57 will have been previously isolated from said magnet and main line current path, as already explained.

Incident to the actuation of sub-station contact 73 by the finger 127 previously referred to, the contacts 85 will be opened, and thereupon the associated tap bell 97 of answer back A¹ will be rendered responsive to the answer back loop 91, so that the associated bell 97 will be energized and, had sub-station S² been operated, the bell 97 of answer back A² would have responded and the lamp 99 would be lighted and the buzzer 101 would sound.

Thereafter, as the code signal of the mechanism 31 is formulated in the main line circuit, such formulation will cause identifying response by the warning bell 95 and by the tap bell 97 of the answer back of the operated station and, in the instance of answer back A², will also cause flashing of its associated lamp 99 and intermittent sounding of the buzzer 101, so that the person who actuated the sub-station will be assured that the intended code signal of the master station M is being formulated in an effective current path of the main circuit. Suitable warning will also be given to others, by the bell 95, that the signal of station M is being formulated in the main circuit responsive to a sub-station.

After the completion of the formulation of the code signal of the mechanism 31, the contacts 45 will be again closed, thus short circuiting the relays 41, 43, and thereby rendering the answer back loop 91 and the signaling devices controlled thereby unresponsive to any ensuing main line signals from other stations.

Had the tripping of the main station M been accomplished by utilization of mechanism such as indicated at sub-station S², the operation would have been the same as just described except that, instead of depressing trigger 117 of station S¹, the handle 157 of station S² would have been moved into proximity or engagement with stop 179, whereupon the mechanism of station S² would have operated as hereinbefore more fully set forth in connection with description of said mechanism, with resultant actuation of its contacts in a manner corresponding to that resultant from actuation of station S¹.

Restoration after tripping

When it is desired to again normally condition the system, actuated sub-station or stations should first be restored. This may be accomplished in the instance of the sub-station mechanism indicated at S¹ by withdrawing the lever 113 from the bellows 111 to the position in which it is latched by the trigger 117. The spring 129 will thereupon extend the bellows 111, creating a partial vacuum therein, and the finger 127 will urge compression of the chamber 119, so that fluid will be drawn through the passage 121 into the bellows 111, the finger 127 will be moved away from and thereby permit re-establishment of normal relationships between contacts 71, 73, 75, 79 and 85.

In the instance of a station such as indicated at S², restoration may be effected in the manner hereinbefore more fully explained in connection 20 with the description of the mechanism of said station.

The shunt loops having been thus restored to normal closed condition, the tripping mechanism associated with magnet 51 of main station M should be restored, by moving arm 33 away from, and thereby permitting re-establishment of normal positioning of, the contacts 41, 49, 64, 65, 66, 67; and effecting latching of said arm 33 in its normal position. The shunt around the windings 30 of the magnet 51 through contacts 66 will thus be opened, and other shunts will be re-established around the windings of this magnet through the loops 55, 57. Short circuits will also be established around the relays 41 and 43, supplemental to the shunt 45.

The various parts will now be restored to condition for causing the formulating mechanism 31 to act responsive to operation of any associated sub-station.

Broken line operation

If one of the sub-stations S¹, S², is set in operation at a time when the main line circuit is standing open as, for example, were the conductor 25 broken, the magnet 51 will not be energized when the shunt loop 55 is opened by previously described movement of any one of the contacts 73 away from its associated contact 71. However, when such contact 73 thereafter engages its associated contact 79, current will flow from one terminal of source GB through source NB, through instrument LI, conductors 21, 23, as well as through station B', through one winding of magnet 51 to terminal 53 (shunt loop 55 being open), thence through part of loop 55 through contacts 73, 79, and the earth, to the other terminal of battery GB; with resultant energization of the magnet 51, starting of the transmitting mechanism 31, opening of contacts 45, 64, 65, 67, 60 47, 49, and closing of contacts 66; whereupon the ground connection established at the operated sub-station will be isolated from the main circuit.

Thereafter, the formulating mechanism 31 will act in a well known manner to establish a ground connection thereat, and to formulate the intended code signal in the main line current path thereby established. The relay 43 will respond to closures of such current path, causing action of answer back instruments identifying the formulated code signal as previously described.

Had the line conductor 23 been broken, instead of the conductor 25, the operation would have been the same as that just described, except that the energization of the magnet 51 would not have

been effected responsive to mere engagement of the sub-station contact 73 with its contact 79, because the current path thus established would have excluded both windings of the magnet 51. Such a path would proceed from one terminal of battery GB, through instrument GI, rectifying unit IR', conductor 27, station B'', conductor 25, shunt 45, contacts 67, loop 57 (including closed contacts 71, 75 of stations S¹, S²) to terminal 53; thence through one side of shunt loop 55, contacts 73, 79 of the operated sub-station and the earth, to the other terminal of source GB.

When, however, movement of contact 73, acting through its extension 83, moves contact 75 away from contact 71 at the actuated sub-station, the loop 57 will be broken, thus diverting current flow from the path just traced, so that it will pass through one winding of the magnet 51, (instead of merely through the loop 57) with resultant energization of said magnet, and consequent formulation of the code signal of the main station M in a path including conductors 25, 27, and relay 41; such formulated signal being also manifested by answer back instruments such as 95, 97, 79, 101.

Operation of short circuited main station

Assuming that the station M is short circuited, as by an accidental connection between conductors 23, 25, it is evident that effective energization of magnet 51 will not result from mere breaking of shunt loop 55, as by movement of contact 73 away from contact 71. When, however, contact 73 engages contact 79 and, acting through extension 83, moves contact 75 away from contact 71, current flow will result in both windings of magnet 51; that through one winding being in the direction normally resultant from current flow in the main circuit while that through the other winding is in the opposite direction from such normal flow.

Consequently, the two windings of magnet 51 will no longer neutralize each other, but will cooperate in causing effective energization of the magnet 51, whereupon the tripping mechanism will act to cause main station M to formulate the intended code signal between line and ground, with resultant response of instrument GI in a well-known manner, the shunt loops being first isolated from the main circuit as previously described, and relays 41 and 43 will act in accordance with the code signal so formulated, to cause manifestation of such signal by answer back instruments.

Pre-signal stroke

It will be noted that operation of a sub-station while the circuit is broken at one side or the other of the main station, or while the main station is short circuited, will result in action of the equipment at the central office preceding the commencement of the code signal formulated by the main station, which response might well be termed a "pre-signal stroke." This is because application of a ground connection at a sub-station then causes current flow through a responsive instrument at the central office, and subsequent cutting off of the shunt loops by the contacts 64, 65, 67 interrupts such current flow.

Such a pre-signal stroke may serve to give notice of the fact that the ensuing code signal is the result of actuation of a sub-station under conditions which have caused the main station to transmit its code through an emergency path. Such a pre-signal stroke should be of special advantage in the instance of a shunted out or short

circuited main station, the condition of which might not otherwise be immediately disclosed.

It will be noted that the interval which elapses between such a pre-signal stroke and the commencement of the ensuing code signal will be substantially that required for the main station mechanism to commence effective signal formulation after having been started in action during broken line or shunted out main circuit conditioning.

Description of Fig. 12

If service conditions are such that it is undesirable that such pre-signal strokes shall be formulated, a change in the manner of control of contact 64 may be so effected that when tripping magnet 51 has been effectively energized responsive to establishment of a ground connection at an associated sub-station, thereby involving current flow through a portion of shunt loop 55 or 57 or through both, as well as through terminal 53 and contacts 64, a resultant path will be rendered effective (as by a suitable lock-up relay) whereby such grounding path will not be interrupted until replacement thereof has been effected by the mechanism 31; with provision such that, in the event that the main station mechanism is of the so-called "perfect non interference and succession type," it will be short circuited incidental to establishing such lock-up path; to the end that such formulating mechanism will act to apply its ground path, even if there might otherwise be current flow therethrough because of continuation of the effectiveness of a sub-station ground connection. Any such supplemental ground path to be finally cleared from the main circuit following effectiveness of the formulating station ground path and prior to the first action of the formulating station to break its ground path incident to signal formulation.

Referring to Fig. 12; modifications are here shown of the master station of Fig. 1, along lines such as just indicated.

Parts shown in Fig. 12 unchanged from Fig. 1 have been given the same reference numbers; and descriptions of such parts and of their operation is not here repeated. Modified and added parts are here given numbers prefixed by the letter "T."

The relay T1 controls normally open contacts T2 and T3, and the winding of its magnet is serially included in the current path between the lower one of the contacts 64 and the interconnected ends of the windings of the magnet 51.

The normally open contacts T4 of the formulating mechanism 31 are so governed as to be closed in the event of defective conditioning of the main circuit during formulating activity of that mechanism, as, for example, in the manner indicated in applicant's aforementioned Patent No. 1,999,859, for the control of the emergency ground connection switch ES there shown.

The one of the contacts T4 which is connected with the earth rests against the supplemental contact T5, so long as said contacts T4 are separated. Closure of said contacts T4 causes isolation of the contact T5 therefrom.

The relay contacts T2 control a current path from the contact T5 to the end of the winding of the magnet of the relay T1 farthest from the interconnected ends of the magnet 51.

The relay contacts T3 control an interconnection between conductors 23 and 25.

From the foregoing, it will be evident that

when energization of the magnet 51 results from association of a ground connection with either or both of the conductors 55, 57, the relay T1 will cause closure of its contacts T2 and T3.

Such closure of the contacts T2 will establish a lock-up path for the magnet of relay T1, which path includes contact T5 and the grounded one of the contacts T4.

Because of the establishment of this path, current flow between the earth and the conductors 23 and/or 25 will continue unaffected by opening of the contacts 64 resultant from energization of the magnet 51.

Closing of the contacts T3 will short circuit the non-interference magnet T6, with the consequence that the formulating mechanism 31 will cause closure of the contacts T4 incidental to ensuing operation of the formulating mechanism, for reasons more fully explained in applicant's aforementioned Patent No. 1,999,859.

Closure of the contacts T4 will result in termination of their connection with the contact T5, with resultant deenergization of the magnet of relay T1 and opening of its contacts T2 and T3.

When the formulating mechanism is of the so-called "plain" or "interfering" type, the magnet T6 will be omitted, the contacts T3 will not be needed, and the contacts T4 will be closed throughout substantially all formulating activity of the mechanism 31.

In any event, when there has been current flow for energization of the magnet 51 resultant from a connection between the earth and conductors 55 and/or 57, the effect of such current flow upon the conditioning of the main line circuit 23, 25, will continue until replaced by grounding of said conductors 23, 25 through the formulating mechanism incidental to closure of its contacts T4.

Busy line operation

If a sub-station is set in operation at a time when a signal is in course of formulation in the main line circuit as, for example, should there be a signal from station B' in course of formulation when one of the sub-stations S¹, S², is set in operation, the resultant action of the various parts will differ from that already described in but two principal respects:

First.—If the main line circuit is being held open incident to signal formulation at a time when the contact 73 of the operated sub-station is moved away from its contact 71, the trip magnet 51 will not be energized until the next ensuing closure in the course of the formulation of such signal.

Due to the delay following such movement of the contact 73 away from the contact 71, and prior to movement of said contact 73 into engagement with ground contact 79 (and incidental establishing of a connection with and movement of contact 75 away from contact 77), the shunt loop 57 will still be intact and the ground connection will not have been rendered effective when the next ensuing closure of the main circuit is effected incident to formulation of the signal of the already acting station therein. Consequently, the tripping mechanism will act responsive to energization of the magnet 51 and thereby cause the main station M to be set in operation before interruption of loop 57 could prevent energization of magnet 51; and isolation of the loops 55, 57 from the main circuit (resultant from opening of contacts 64, 65, 67) will therefore occur before closing of the circuit

ground connection to either of the shunt loops, thus avoiding needless interference with the signal already in course of formulation in the main circuit.

- 5   *Second.*—Unless the closure which causes effective energization of the magnet 51 happens to be that following the conclusion of the signal of a previously acting main line station, it will be understood that if the mechanism 31 includes 10 a so-called "non-interference" feature, such feature will prevent any interruption by station M of the code signal already in course of formulation, and if said mechanism 31 includes a so-called "succession" feature such feature will 15 cause the code signal of station M to be formulated promptly after the main line is in condition therefor. If mechanisms of stations M and B' are of "plain" or "interfering" type (such, for example, as those shown and described in applicant's Patent No. 1,528,596, dated March 3, 1925), station M will proceed with the formulation of its signal just as if no other station was in action, and this will not cause station B' to discontinue its formulating activity. Throughout 20 such concurrent formulating activities, each formulating closure at station M will result in current flow through a path from + terminal of battery GB through GI, IR', 27, B'', 25, 41, 31, and through the earth to — terminal of said battery. Each formulating break of station M will interrupt that path. Correspondingly, each formulating closure at station B' will result in current flow through a path from + terminal of battery NB, through LI, 21, B', thence to and 25 through the earth and battery GB, to — terminal of battery NB. Each formulating break of station B' will interrupt this path.

It is evident that, under the conditions just indicated, the signals of stations M and B' will 30 be fully and correctly manifested by the instruments GI and LI, respectively.

The response of answer back instruments under busy line conditions will correspond with that under normal conditions already herein explained, in that, following tripping of the main station, the associated answer back instruments will manifest all ensuing signaling impulses to which either or both relays 41, 43, respond.

Thus, if the tripped master station is of the 40 non-interference and succession type and signaling impulses from some other main line station are formulated before such master station takes control of the main line, the answer back instruments will manifest all such impulses, thus enabling the sub-station user to know that the code signal of the main station which should respond to his call is being delayed because priority has been accorded to some other signal.

Should the master station be of the interfering type, the answer back instruments will indicate whether the code signal of such station is being formulated over a then effective main line path in one direction or the other from the main station. If other interfering type main stations 55 are active at both sides of a tripped interfering type station throughout its action, absence of answer back will give warning that the intended signal has not been sent.

Simultaneous sub-station operation

If two or more sub-stations are operated at or about the same time and while the main circuit is closed, the tripping magnet will be energized as soon as one of the shunt loops is interrupted, with results as already more fully described.

Correspondingly, if the main circuit is open, or is shunted around the main station, the result of the actuation of two or more stations will be the same as if but one station were operated; except that, sub-stations operated one after another under such circumstances, will cause energization of the tripping magnet only when a sub-station applies its ground connection to a loop at a time when such loop is not broken by any other sub-station situated therein between the terminal 53 and such ground connection.

Results of shunt loop defects

Accidental rupture of either shunt loop 55 or 57, while the system is otherwise in normal condition, will result in tripping of the master box with consequent formulation of its signal and incidental cutting off of the shunt loops.

Simultaneous breakage of both loops will not cause tripping of the master station, but will add the resistance of both windings of magnet 51 to the main line circuit, thus tending to cause a change in current flow which may be detected at the central office.

If one shunt loop is broken at one side of an actuated sub-station and the other loop at the other side, tripping of the main station will nevertheless be accomplished, because the sub-station ground connection will then be applied to both loops 55 and 57, assuring that so long as either loop is intact between an actuated station and terminal 53, energization of magnet 51 may be effected. There will, however, be no response to operation of a sub-station when both loops 55 and 57 are broken between such station and terminal 53.

Grounding of either or both of the shunt loops may be readily detected from the central office, but will not cause tripping of the master station so long as both of the shunt loops are unbroken, and will not prevent tripping of the master station from sub-stations while conditions of other portions of the system remain normal.

Operation of Fig. 6

Operation of a system arranged in accordance with Fig. 6 is substantially the same as that of a system in accordance with Fig. 1, except as follows:

The first step of sub-station contact actuation establishes a connection between contacts 643 and 649 through contact 653. If, during this connection, the main line circuit is closed, either because it is in normal condition and no other stations are active or incident to a closure in the signal of some other station, the magnet 51 will be energized and will effect tripping of the master station, whereupon contact 666 will be moved into engagement with contact 664 and carry same away from contact 665, at the same time opening contacts 667, 668, and 669; thus first short circuiting the shunt loops and the windings of magnet 51 and then isolating said loops from the main line.

If the main path is not closed while contact 653 connects contacts 643 and 649, the sub-station mechanism will, after a suitable predetermined interval (such as previously referred to) act to cause contact 653 to be moved away from contact 643 and into engagement with contact 655, thus applying a ground connection between the two windings of magnet 51, so that said magnet will be energized by current flow either from conductor 23 or conductor 25, or co-operatively

from both of these conductors in parallel, should there be an accidental connection between them.

Operation of Fig. 7

5 Operation of a system arranged in accordance with Fig. 7 differs from that herein before described in connection with other embodiments of this invention, in respects as follows:

Under normal conditions, substantially all of the main line current is diverted around magnet 751 through shunt loop 757.

Actuation of station S⁷¹ first results in opening of contacts 759, thus suspending normal direction of current flow in loop 757, because of the blocking action of rectifiers 769.

After a predetermined time (such as hereinbefore described) contacts 765 are closed, thus applying a ground connection intermediate to the ends of the rectifier or asymmetric conductor 769. If, now, there is a suitable positive electromotive force between conductor 23 and the earth, current will flow through the winding of magnet 751 and the lower portion of asymmetric conductor 769 to the ground connection, thus effectively energizing said magnet. If there is a like negative potential between conductor 25 and the earth, current will flow from the earth through contacts 765, the upper portion of asymmetric conductor 769 and the winding of magnet 751 to conductor 25.

Correspondingly, in using station S⁷², the switch 759' is moved so as to interrupt the current path therethrough, preferably, at first, without bringing switch 765' in position to close its ground connection. Then, after a suitable time, switch 765' is moved to close its ground connection. Otherwise, its action will correspond with that of station S⁷¹.

It will be evident that if, for example, in a station such as S⁷², the ground connection is established at or about the time that the shunt loop path is broken and when the main line circuit is closed, there will be a needless pre-signal stroke manifested at the central office, but the operation of the system will be otherwise unchanged.

In the instance of station S⁷³, the shunt loop is first interrupted between contacts 759, a ground connection is next applied between contacts 781 and 783, then between 783 and both 781 and the upper contact of 759, after which 783 is moved away from 781. While contacts 781 and 783 are connected, the lower end of the winding of magnet 751 is grounded, during the short time that 783 connects both 781 and 759, both ends of the winding of magnet 751 are grounded, and when contact 783 connects the upper contact of 759 only, the upper terminal of the winding of magnet 751 is grounded. In other words, after opportunity has been afforded for the magnet 751 to be energized by normal current flow in the main line, a ground connection is applied first to one terminal of the winding and then to the other terminal of the winding, so that if there is a potential between either end of this winding and the earth, this magnet will be effectively energized, and the connection to one end is not broken until that to the other end has become effective, so as to avoid a needless extra pre-signal stroke in the central office.

Operation of Fig. 8

Actuation of either of the magneto generators 871, 871, will cause its normally closed contact 873 to be opened, thus interposing the resistance

of the generator and that of the bell 875 into the normally closed shunt loop around the winding of magnet 851. Thereupon, if there is current flow between conductors 23 and 25, said magnet will be effectively energized. In the absence of current flow between conductors 23 and 25, the current resultant from the actuation of the magneto generator will cause energization of the magnet 851 and will cause the associated bell 875 to sound. If there is an accidental short circuit between conductors 23 and 25, the reactance 865 will cause sufficient of the alternating current from the active generator to be diverted through the winding of magnet 851 to assure effective energization of this magnet.

When the master station has been tripped, as just indicated, its contacts 857, 859 will be moved away from its contacts 853, 855, and into engagement with its contacts 861, 863, respectively. This will isolate the loop 867 from the magnet 851 and from the main line conductors 23 and 25, and will prevent further response of the associated bell 875 other than during signaling closures in the main line circuit which effect energization of either or both of the relays 841, 843. It will therefore be evident that continued operation of the magneto generator will cause its associated bell to sound the code signal formulated in the main circuit in a manner analogous to that already described in connection with Fig. 1, other than that, in the instance of the system of Fig. 8, no extra wires are required between the master station and the sub-stations for effecting the operation of the answer back bells, and the further fact that an associated bell 875 will sound throughout operation of its generator 871, so long as the shunt loop 867 remains closed even should tripping of the master station not be accomplished.

Operation of system of Fig. 9

The relationship between the magneto generators 971, 971 and the magnet 951 are similar to those of corresponding parts of Fig. 8, but the relationship of the answer back bells 975, 975 differs in that these bells are connected in a separate answer back loop 969, controlled by bell-shunting switches 977, 977 at the respective generators.

Operation of a generator 971 will effect tripping of the master station through energization of the magnet 951 in a manner corresponding to that described in connection with Fig. 8.

Until the master station has been effectively tripped, the bells 975, 975 will remain silent.

After the master station has been tripped, resultant movement of contacts 957, 959, into engagement with contacts 961, 963, respectively, will connect the answer back loop 969 in series with the sub-station loop 967 through the local contacts of relays 941, 943.

Thereafter, continued operation of the associated generator 971 will cause its bell 975 to sound (shunting contacts 977 being held open by the operation of the generator) such sounding being co-extensive with closures of the contacts of either or both relays 941, 943.

Alternative embodiments

While certain specific embodiments of this invention have been illustratively indicated in the accompanying drawings and hereinbefore described in considerable detail, it should be understood that this invention is not limited to such embodiments or details, nor to any of them, except insofar as they are defined by limitations

within the terms of the annexed claims, in which it is intended to claim all generic and specific features inherent to this invention as broadly as is permissible in view of the prior art, inclusive of all statements of the scope of this invention which, as a matter of language, might be said to fall between the following.

I claim:

1. A signaling system having a normally energized main circuit, signaling mechanism including an electromagnet having winding portions connected serially with said circuit and opposingly with each other, two comparatively low resistance current paths normally shunting such winding portions, respectively, for preventing effective energization of said magnet, an independent conductor, means for maintaining an electromotive force between said circuit and said conductor, and sub-station mechanism associated with said paths, and operable for functionally interrupting one of said paths for causing effective energization of said magnet from normal main circuit current flow, for then likewise interrupting the other of said paths and for connecting said conductor with the end of one of said paths which leads to such end of the associated winding portion as is directly connected with an end of the other winding portion.
2. A signaling system having a normally energized main circuit, signaling mechanism including an electromagnet having winding portions connected serially with said circuit and opposingly with each other, two comparatively low resistance current paths normally shunting such winding portions, respectively, for preventing effective energization of said magnet, an independent conductor, means for maintaining an electromotive force between said circuit and said conductor, and sub-station mechanism associated with said paths, and operable for functionally interrupting one of said paths for a time measured by the operation of said sub-station mechanism for causing effective energization of said magnet from normal main circuit current flow, for then likewise interrupting the other of said paths and for connecting said conductor with the end of one of said paths which leads to such end of the associated winding portion as is directly connected with an end of the other winding portion.
3. A signaling system having a normally energized main circuit, tripping means including an electromagnet having winding portions connected serially with said circuit and opposingly with each other, said means trippable responsive to energization of said magnet, two comparatively low resistance current paths normally shunting such winding portions, respectively, for preventing effective energization of said magnet, controlling mechanism responsive to tripping of said first named means for isolating said paths from said circuit, an independent conductor, means for maintaining an electromotive force between said circuit and said conductor, and sub-station mechanism associated with said paths, and operable for functionally interrupting one of said paths for a time measured by the operation of said sub-station mechanism for causing effective energization of said magnet from normal main circuit current flow, for then likewise interrupting the other of said paths and for connecting said conductor with the end of one of said paths which leads to such end of the associated winding portion as is directly connected with an end of the other winding portion.

4. A signaling system having a normally energized main circuit, tripping means including an electromagnet having winding portions connected serially with said circuit and opposingly with each other, said means trippable responsive to energization of said magnet, two comparatively low resistance current paths normally shunting such winding portions, respectively, for preventing effective energization of said magnet, controlling mechanism responsive to tripping of said first named means for isolating said paths from said circuit, an independent conductor, means for maintaining an electromotive force between said circuit and said conductor, and sub-station mechanism associated with said paths, and operable for functionally interrupting one of said paths for a time measured by the operation of said sub-station mechanism for causing effective energization of said magnet from normal main circuit current flow, for then likewise interrupting the other of said paths and connecting said conductor with portions of respective ones of said paths which lead to directly interconnected ends of said winding portions.

5. A signaling system having a normally energized main circuit, mechanism for formulating signaling impulses in said circuit, tripping means including an electromagnet having winding portions connected serially with said circuit and opposingly with each other, said means trippable responsive to energization of said magnet for rendering active said mechanism, two comparatively low resistance current paths normally shunting such winding portions, respectively, for preventing effective energization of said magnet, controlling mechanism responsive to tripping of said first named means for isolating said paths from said circuit, an independent conductor, means for maintaining an electromotive force between said circuit and said conductor, and sub-station mechanism associated with said paths, and operable for functionally interrupting one of said paths for a time measured by the operation of said sub-station mechanism for causing effective energization of said magnet from normal main circuit current flow, for then likewise interrupting the other of said paths and connecting said conductor with portions of respective ones of said paths which lead to directly interconnected ends of said winding portions.

6. A signaling system having a normally energized main circuit, mechanism for formulating signaling impulses in said circuit, tripping means including an electromagnet having winding portions connected serially with said circuit and opposingly with each other, said means trippable responsive to energization of said magnet for rendering active said mechanism, two comparatively low resistance current paths normally shunting such winding portions, respectively, for preventing effective energization of said magnet, controlling mechanism responsive to tripping of said first named means for isolating said paths from said circuit, an independent conductor, means for maintaining an electromotive force between said circuit and said conductor, and sub-station mechanism associated with said paths, and operable for functionally interrupting one of said paths for a time measured by the operation of said sub-station mechanism and longer than the longest open circuit interval incident to the formulation of any signal in said circuit for causing effective energization of said magnet

from normal main circuit current flow, for then likewise interrupting the other of said paths and connecting said conductor with portions of respective ones of said paths which lead to directly interconnected ends of said winding portions.

7. A signaling system having a normally energized main circuit, mechanism for formulating signaling impulses in said circuit, tripping means including an electromagnet having winding portions connected serially with said circuit and opposingly with each other, said means trippable responsive to energization of said magnet for rendering active said mechanism, two comparatively low resistance current paths normally shunting such winding portions, respectively, for preventing effective energization of said magnet, controlling mechanism responsive to tripping of said first named means for isolating said paths from said circuit and for shunting said magnet independently of said paths, an independent conductor, means for maintaining an electromotive force between said circuit and said conductor, and sub-station mechanism associated with said paths, and operable for functionally interrupting one of said paths for a time measured by the operation of said sub-station mechanism and longer than the longest open circuit interval incident to the formulation of any signal in said circuit for causing effective energization of said magnet from normal main circuit current flow, for then likewise interrupting the other of said paths and connecting said conductor with portions of respective ones of said paths which lead to directly interconnected ends of said winding portions.

8. A signaling system having a normally energized main circuit, mechanism for formulating signaling impulses in said circuit, tripping means including an electromagnet having winding portions connected serially with said circuit and opposingly with each other, said means trippable responsive to energization of said magnet for rendering active said mechanism and fully restorable only during deenergization of said magnet, two comparatively low resistance current paths normally shunting such winding portions, respectively, for preventing effective energization of said magnet, controlling mechanism responsive to tripping of said first named means for isolating said paths from said circuit and for shunting said magnet independently of said paths, an independent conductor, means for maintaining an electromotive force between said circuit and said conductor, and sub-station mechanism associated with said paths, and operable for functionally interrupting one of said paths for a time measured by the operation of said sub-station mechanism and longer than the longest open circuit interval incident to the formulation of any signal in said circuit for causing effective energization of said magnet from normal main circuit current flow, for then likewise interrupting the other of said paths and connecting said conductor with portions of respective ones of said paths which lead to directly interconnected ends of said winding portions and finally interrupting such connections and reclosing said other path.

9. A signaling system having, in combination, a main circuit, an independent conductor, means for maintaining an electromotive force between said circuit and said conductor, means for formulating signaling impulses by intermittently suspending the normal conditioning of said circuit, means for rendering active said formulating

means, said activating means comprising an electromagnet suited for energization from said circuit, conductors providing current paths for variably associating said magnet with said circuit and with said independent conductor, sub-station mechanism comprising means for governing interconnections between certain of said conductors, said governing means being normally conditioned to effect a relationship between said conductors for preventing functional energization of said magnet, means set in action by operation of said mechanism for causing an alteration in the conditioning of said governing means for a time measured by the operation of said mechanism and longer than the longest suspension of normal conditioning of said circuit incident to the formulation of any signal therein and for thereafter causing another alteration in the conditioning of said governing means, said governing means being conditioned by said mechanism during the first named one of said alterations for effecting a relationship between said conductors which associates said magnet with said circuit for energization from the normally effective current path therein, and, during the second named one of said alterations, for effecting a relationship between said conductors for rendering said magnet responsive to current flow between said independent conductor and portions of said main circuit situated at one side or the other of said formulating means.

10. A signaling system having signaling mechanism including an electromagnet having two independent winding portions, a comparatively low resistance current path connecting an end of one of said winding portions to an end of the other of said portions in opposing relationship, a second such path having one end thereof connected to the remaining end of one of said winding portions, a normally energized main circuit in which said paths and winding portions are serially connected, an independent conductor, means for maintaining an electromotive force between said circuit and said conductor, and sub-station mechanism associated with said paths and operable for interconnecting said paths for causing effective energization of said magnet from normal main circuit current flow and thereafter interrupting such connection and connecting said conductor with said first named current path for effecting energization of said magnet in the absence of normal main circuit current flow.

11. A signaling system having a normally energized main circuit, mechanism for formulating signals in said circuit, an electromagnet with two independent winding portions, tripping means responsive to energization of said magnet for rendering active said mechanism, a comparatively low resistance current path connecting an end of one of said winding portions to an end of the other of said portions in opposing relationship, a second such path having one end thereof connected to the remaining end of one of said winding portions, said paths and winding portions serially connected in said circuit, an independent conductor, means for maintaining an electromotive force between said circuit and said conductor, and sub-station mechanism associated with said paths, and operable for interconnecting said paths for a time measured by the operation of said sub-station mechanism for causing effective energization of said magnet from normal main circuit current flow, and thereafter interrupting such connection and connecting said conductor with said first named current path for effecting ener-

gization of said magnet in the absence of normal main circuit current flow.

12. A signaling system having a normally energized main circuit, mechanism for formulating signals in said circuit, an electromagnet with two independent winding portions, tripping means responsive to energization of said magnet for rendering active said mechanism, a comparatively low resistance current path connecting an end of one of said winding portions to an end of the other of said portions in opposing relationship, a second such path having one end thereof connected to the remaining end of one of said winding portions, said paths and winding portions serially connected in said circuit, an independent conductor, means for maintaining an electromotive force between said circuit and said conductor, and sub-station mechanism associated with said paths and operable for interconnecting said paths for a time measured by the operation of said sub-station mechanism and longer than the longest open circuit interval incident to the formulation of any signal in said circuit, for causing effective energization of said magnet from normal main circuit current flow, and thereafter interrupting such connection and connecting said conductor with said first named current path for effecting energization of said magnet in the absence of normal main circuit current flow.

13. A signaling system having a normally energized main circuit, mechanism for formulating signals in said circuit, an electromagnet with two independent winding portions, tripping means responsive to energization of said magnet for rendering active said mechanism and fully restorable only during deenergization of said magnet, a comparatively low resistance current path connecting an end of one of said winding portions to an end of the other of said portions in opposing relationship, a second such path having one end thereof connected to the remaining end of one of said winding portions, said paths and winding portions serially connected in said circuit, an independent conductor, means for maintaining an electromotive force between said circuit and said conductor, and sub-station mechanism associated with said paths and operable for interconnecting said paths for a time measured by the operation of said sub-station mechanism and longer than the longest open circuit interval incident to the formulation of any signal in said circuit, for causing effective energization of said magnet from normal main circuit current flow, and thereafter interrupting such connection and connecting said conductor with said first named current path for effecting energization of said magnet in the absence of normal main circuit current flow, and finally interrupting such connection.

14. A signaling system having a normally energized main circuit, mechanism for formulating signaling impulses in said circuit, tripping means including an electromagnet associated for energization from said circuit, said means trippable responsive to energization of said magnet for rendering active said mechanism, and fully restorable only during deenergization of said magnet, a comparatively low resistance current path normally shunting said magnet for preventing effective energization thereof, controlling mechanism responsive to tripping of said means for isolating said path from said circuit and for shunting said magnet independently of said path, an independent conductor, means for maintaining an electromotive force between said cir-

cuit and said conductor, and sub-station mechanism associated with and operable for functionally interrupting said path for causing effective energization of said magnet, for a time measured by the operation of said sub-station mechanism and longer than the longest open circuit interval incident to the formulation of any signal in said circuit, thereafter connecting said conductor first with one side of such interrupted path, then with both of such sides, next exclusively with the other of such sides, and for finally interrupting such connection.

15. A signaling system having a normally energized main circuit, mechanism for formulating signaling impulses in said circuit, tripping means including an electromagnet associated for energization from said circuit, said means trippable responsive to energization of said magnet for rendering active said mechanism, a comparatively low resistance current path normally shunting said magnet for preventing effective energization thereof, controlling mechanism responsive to tripping of said means for isolating said path from said circuit, an independent conductor, means for maintaining an electromotive force between said circuit and said conductor, and sub-station mechanism associated with and operable for functionally interrupting said path, to cause effective energization of said magnet, for a time measured by the operation of said sub-station mechanism, and thereafter connecting said conductor first with one side of such interrupted path, next with both of such sides, and then exclusively with the other of such sides.

16. A signaling system having a normally energized main circuit, mechanism for formulating signaling impulses in said circuit, tripping means including an electromagnet associated for energization from said circuit, said means trippable responsive to energization of said magnet for rendering active said mechanism, a comparatively low resistance current path normally shunting said magnet for preventing effective energization thereof, controlling mechanism responsive to tripping of said means for isolating said path from said circuit, an independent conductor, means for maintaining an electromotive force between said circuit and said conductor, and sub-station mechanism associated with and operable for functionally interrupting said path, to cause effective energization of said magnet, for a time measured by the operation of said sub-station mechanism, for thereafter independently connecting said conductor with one and the other of the sides of such interrupted path.

17. A signaling system having a normally energized main circuit, mechanism for formulating signaling impulses in said circuit, tripping means including an electromagnet associated for energization from said circuit, said means trippable responsive to energization of said magnet for rendering active said mechanism, a comparatively low resistance current path normally shunting said magnet for preventing effective energization thereof, controlling mechanism responsive to tripping of said means for isolating said path from said circuit, an independent conductor, means for maintaining an electromotive force between said circuit and said conductor, and sub-station mechanism associated with and operable for functionally interrupting said path, to cause effective energization of said magnet, for a time measured by the operation of said sub-

station mechanism, and longer than any open circuit interval within any main circuit signal, and thereafter connecting said conductor with a side of such interrupted path.

- 5 18. A signaling system having a normally energized main circuit, mechanism for formulating signaling impulses in said circuit, tripping means including an electromagnet associated for energization from said circuit, said means trippable responsive to energization of said magnet for rendering active said mechanism, a comparatively low resistance current path normally shunting said magnet for preventing effective energization thereof, controlling mechanism responsive to tripping of said means for isolating said path from said circuit, an independent conductor, means for maintaining an electromotive force between said circuit and said conductor, and sub-station mechanism associated with and operable for functionally interrupting said path, to cause effective energization of said magnet, for a time measured by the operation of said sub-station mechanism, and longer than any open circuit interval within any main circuit signal, and for thereafter effecting a connection between said independent conductor and said shunt path for rendering said magnet responsive to resultant current flow.
- 10 19. A signaling system having a normally energized main circuit, signaling mechanism including an electromagnet associated for energization from said circuit, a comparatively low resistance current path normally shunting said magnet for preventing effective energization thereof, an independent conductor, means for maintaining an electromotive force between said circuit and said conductor, and sub-station mechanism including a multisection asymmetric conductor and means operable for effecting association of said asymmetric conductor with said path to oppose normal direction of current flow therethrough for a time measured by the operation of said sub-station mechanism and thereafter connecting said independent conductor intermediate such asymmetric conductor sections.
- 15 20. Sub-station mechanism for association with an auxiliary system having a main line circuit including signal formulators, said mechanism having, in combination, five separately insulated conductors, means for governing interconnections between said conductors, said means being normally conditioned to interconnect two of said conductors in one group and another two of said conductors in a second group, each of said groups independent of the other and of the fifth of said conductors, timing means set in action by operation of said mechanism for causing said governing means to break the interconnection between the conductors of one of said groups for a time measured by the action of said timing means and longer than the longest suspension of normal conditioning of an intendedly associated main circuit incident to signal formulation therein and for thereafter breaking the interconnection between the conductors of the other of said groups and connecting said fifth conductor with one of the other of said conductors.
- 25 21. Sub-station mechanism for association with an auxiliary system having a main line circuit including signal formulators, said mechanism having, in combination, three separately insulated conductors, means for governing interconnections between said conductors, said means being normally conditioned to intercon-
- 30 35 40 45 50 55 60 65 70

nect two of said conductors independently of the third thereof, timing means set in action by operation of said mechanism for causing said governing means to break said interconnection for a time measured by the action of said timing means and longer than the longest suspension of normal conditioning of an intendedly associated main circuit incident to signal formulation therein and for thereafter establishing a connection of comparatively short duration between one of the normally interconnected two and the third of said conductors.

22. Auxiliary system sub-station mechanism operable to effect a plurality of functional steps and having circuit controlling means for interrupting a normally closed current path incident to one of said steps and successively and independently connecting a conductor normally isolated therefrom with one end and the other of such interrupted path incident to succeeding such steps, said mechanism involving means, set in action incident to said first step, for delaying the accomplishment of such succeeding steps for a time measured by the operation thereof and longer than any open circuit interval within any signal of an intended associated main circuit.

23. Auxiliary system sub-station mechanism having a plural section asymmetric conductor, circuit controlling means normally providing a low resistance current path, and mechanism operable for rendering effective said conductor for opposing current flow in one direction through such path and for connecting a previously isolated conductor intermediate such asymmetric sections, said mechanism involving means for delaying the establishment of such connection for a time measured by the operation thereof.

24. Sub-station mechanism for association with an auxiliary system having a main line circuit including signal formulators, said mechanism having, in combination, three separately insulated conductors, means for governing interconnections between said conductors, said

means being normally conditioned to interconnect two of said conductors independently of the third thereof, timing means set in action by operation of said mechanism for causing said governing means to break said interconnection for a time measured by the action of said timing means and longer than the longest suspension of normal conditioning of an intendedly associated main circuit incidental to signal formulation therein and for thereafter establishing a connection between one of the normally interconnected two and the third of said conductors.

25. A signaling system having, in combination, a main circuit, an independent conductor, means for maintaining an electromotive force between said circuit and said conductor, a signal device, means for rendering active said device, said activating means comprising an electromagnet suited for energization from said circuit, conductors providing current paths for variously associating said magnet with said circuit and with said independent conductor, sub-station mechanism comprising means for governing interconnections between certain of said conductors, said governing means being normally conditioned for effecting a relationship between said conductors whereby functional energization of said magnet is prevented, means set in operation by action of said mechanism for altering the relationship between said conductors whereby to associate said magnet with said circuit for energization from the normally effective current path therein, for continuing such alteration of the conditioning of said governing means for a time measured by the operation of said altering means and longer than the longest suspension of normal conditioning of said circuit incident to the formulation of any signal therein, and for thereafter effecting a relationship between said conductors whereby to interconnect said independent conductor with said circuit and render said magnet responsive to resultant current flow.
